US00D518725S

(12) **United States Design Patent** (10) **Patent No.:** **US D518,725 S**
Eble (45) **Date of Patent:** **** Apr. 11, 2006**

(54) **CONTAINER**

(75) Inventor: **Raymond C. Eble**, Sugarloaf, PA (US)

(73) Assignee: **Harbison Corporation**, St. Louis, MO (US)

(**) Term: **14 Years**

(21) Appl. No.: **29/202,277**

(22) Filed: **Mar. 29, 2004**

(51) **LOC (8) Cl. 09-01**

(52) **U.S. Cl. D9/502; D9/520**

(58) **Field of Classification Search** D9/500, D9/501–504, 516, 529, 536–539, 549–550, D9/557–558, 723–729; D7/597, 619.1, 608; 215/381–385, 379; 220/660, 666, 669, 675

See application file for complete search history.
